UNITED STATES PATENT OFFICE

90,944

DESIGN FOR A RADIATOR CAP

Edellard L. Gilbert, Fort Bayard, N. Mex.

Application September 6, 1933. Serial No. 49,209

Term of patent 14 years

To all whom it may concern:

Be it known that I, EDELLARD L. GILBERT, a citizen of the United States of America, residing at Fort Bayard, in the county of Grant and State of New Mexico, have invented a new, original, and ornamental Design for a Radiator Cap, of which the following is a specification, reference being had to the accompanying drawing, forming a part thereof.

Figure 1 is a top plan view of a radiator cap showing my new design, and

Figure 2 is a side elevational view of the same.

I claim:

The ornamental design for a radiator cap as shown.

EDELLARD L. GILBERT.
